UNITED STATES PATENT OFFICE.

JOHN A. KAYE, OF SAULT STE. MARIE, ONTARIO, CANADA.

PACKAGE TIE.

Application filed November 23, 1922. Serial No. 602,900.

To all whom it may concern:

Be it known that I, JOHN A. KAYE, a subject of the King of Great Britain, residing at Sault Ste. Marie, in the Province of Ontario and Dominion of Canada, have invented certain new and useful Improvements in Package Ties, of which the following is a specification.

The present invention relates to a package tie of that general character which includes a string and means for securing the ends of the string without knotting or mutilating the same, so that the string can be used repeatedly for the purpose of fastening packages. Where it is possible to use a device of this kind the expense of providing a new length of string for each package to be fastened is avoided and the economy thus made possible may in many instances be considerable.

Among the objects of the invention is to provide a package tie which is comparatively simple and inexpensive in its construction, which can be readily utilized for securing bundles of letters or the like, which can be easily handled, and which can be used repeatedly, thereby avoiding the necessity of providing a new length of string for each package to be secured.

The invention also contemplates the provision of the string clamping element with means for initially engaging the package so that it is held in proper position thereon while the string is being drawn around the package, thereby facilitating the rapid application of the package tie and enabling large numbers of packages to be secured in a minimum amount of time.

With the above and other objects in view, the invention consists in certain combinations and arrangements of the parts as will more fully appear as the description proceeds, the novel features thereof being pointed out in the appended claims.

For a full understanding of the invention reference is to be had to the following description and accompanying drawings in which,

Figure 1 is a perspective view of a package which has been secured with a package tie constructed in accordance with the invention.

Figure 2 is an enlarged detail perspective view of the string engaging element of the

package tie, the two parts of the string engaging element being shown as separated.

Figure 3 is a transverse sectional view through the string engaging element of the package tie, the two parts thereof being separated as in the preceding figure.

Figure 4 is a detail view of the clamping head, showing a modification in which a lock is used, portions being broken away and shown in section.

Corresponding and like parts are referred to in the following description, and indicated on all of the views of the drawings by like reference characters.

Referring to the drawings, which illustrate one of many possible embodiments of the invention, the reference character A designates a package which is secured by means of a string 1. The string is drawn or wrapped around the package in the usual manner and the free ends thereof are secured by the string fastening device which is indicated as an entirety by the reference character B. The string is fastened without the necessity of knotting or mutilating the same, so that there is no need for the string to be cut and thrown away when the package is opened and the string can be used repeatedly.

The string fastening device includes a disc or base plate 2 which is provided upon the bottom thereof with a vacuum cup member 3, and upon the top thereof with a clamping device which is adapted to engage and grip the ends of the string after the string has been drawn tightly around the package.

The vacuum cup member 3 may be formed of suitable material, such as soft rubber, and fastened to the base 2 in any suitable manner. When the vacuum cup is forcibly pressed against a smooth flat surface or one side of the package to be secured, it will operate in the usual manner to grip the package and hold the base plate 2 in position thereon. After this has been done the operator has both hands free for use in drawing the string around the package and bringing the ends thereof into a proper engagement with the string clamping means on the base plate.

Any other equivalent means for initially holding the base plate in position upon the package may be substituted for the vacuum cup 3, since it is only necessary that some simple and convenient

means be provided for temporarily holding the string clamping device in position upon the package when applying the package tie, so that the operator will have both hands free for manipulating the string and can work quickly.

A circular flange 4 projects upwardly from the base plate 2, and this flange is provided at suitable intervals with string receiving notches 5. The flange is threaded to receive a similar flange 6, which is carried by a suitable finger piece 7. After the string 1 has been drawn around the package the ends thereof are inserted within appropriate notches 5 of the flange 4. The clamping head 6 is screwed into the flange 4 in such a manner that the portions of the string which extend through the notches 5 are securely gripped and engaged by the flange 6. The flange or clamping element 6 can be screwed tightly into position and brought into a forcible engagement with the string so that the string is tightly gripped and held in proper position upon the package.

When it is desired to release the package it is merely necessary to unscrew the clamping head 6 and thereby release the ends of the string, after which the string engaging device can be quickly removed from the package. The string clamping device can be used in connection with different lengths of string depending upon the size of the package to be secured, and there is no need to knot the string when fastening the package or to cut the string when opening the package. It is thought that the device can be used to advantage by postal clerks in securing packages of letters, and an enormous saving could be made in the expense of cord or twine which is required to secure these bundles, and which under ordinary conditions is used once and then thrown away.

An important feature of the invention is the provision of means upon the string clamping device for temporarily fastening the device to the package so that it is held initially in position without any resulting injury to the package, thereby leaving both hands of the operator free for use in positioning the string upon the package and clamping the ends of the string. This enables the operator to work with great rapidity so that there is no loss of time in securing a package with this device.

While I have illustrated and described one particular embodiment of the invention, it will be understood that many modifications and changes can be made in the details of construction without departing from the spirit of the invention.

A slight modification is shown by Figure 4 in which means is provided for locking the clamping head in operative position, thereby rendering it impossible for the package tie

to work loose even when subjected to much handling and continuous vibration. The inside of the clamping head may be provided with a shallow casing 9 within which a locking bolt 10 is slidably secured to the top plate 7 of the clamping head by any suitable means, such as the rivets 11. The locking bolt may be directed in its sliding movements in any suitable manner, as by engagement with guide notches in the ends of the casing. Lugs 12 on the locking bolt are adapted to be engaged by the web portion of an ordinary key for sliding the locking bolt into and out of operative positions. A spring 13 may frictionally engage the locking bolt to hold it against accidental movement. The top of the clamping head is provided with an ordinary key hole opening 14 through which the key can be readily inserted or removed. The end of the locking bolt may pass through an opening in the flange 6 of the clamping head and engage the notches 5 of the flange 4 or other suitable cut-away portions in the said flange 4. This is merely a conventional showing of a lock, and it will be understood that any suitable form of locking means may be used in the same manner. When the clamping head is thus locked there is no danger that it will be jarred loose and caused to release the cord or twine before it is desired to open the package.

Having thus described my invention what I claim as new and desire to secure by Letters Patent is,

1. In a package tie, the combination with a body portion, of suction means for detachably attaching the body portion to a package, and a string engaging device upon the body portion.

2. A package tie including a body portion, a suction cup on the body portion for detachably engaging the package, and a string engaging device carried by the body portion.

3. A package tie including a plate, suction means on one side of the plate for detachably engaging a package to initially position the device thereon, and a string engaging device on the opposite side of the plate.

4. A package tie including a plate, a suction cup upon one side of the plate for detachably engaging the package to initially position the tie thereon, and a string engaging clamp on the opposite side of the plate for clamping the ends of the string after the string has been wrapped around the package.

5. In a device of the character described, a string fastening element including a base plate, means carried by the base plate and arranged upon one side thereof for removably engaging a package to initially position the base plate thereon, a flange projecting from the opposite side of the base plate

and provided with string receiving cut-away portions, and a clamping head threaded in the flange and arranged for cooperation therewith to grip portions of the string received within the said cut-away portions of the flange.

6. In a device of the character described, the combination of a base member, a string

receiving projection thereon, a clamping head detachably engaging the said projection and cooperating therewith to grip the string, and key controlled locking means for holding the clamping head in operative position.

In testimony whereof I affix my signature.
JOHN A. KAYE.
